POURING NOZZLE

René Cantoni, Ugine, France, assignor to Société d'Electrochimie, d'Electrométallurgie et des Acieries Électriques d'Ugine, Paris, France, a corporation of France

Application February 10, 1938, Serial No. 189,801
In France March 31, 1937

1 Claim. (CL 22—84)

The cooling of a fused metal while it is flowing by gravity from a receptacle, furnace or ladle through a pouring orifice formed by a nozzle, and the variation of the height of the metal above this orifice, give rise to variations in the conditions of casting in an unfavourable manner and often give rise to surface or internal defects of the cast ingots or pieces.

To avoid these disadvantages the section of the pouring nozzle placed in the pouring orifice has been varied, during the course itself of the casting.

The processes most utilized consist either in constituting the nozzle of a material which is attacked by the metal during and in proportion to the casting which ensures an automatically increasing flow section, or in adjoining to the normal nozzle an auxiliary nozzle of smaller section which can be taken off during the pouring or replaced by another nozzle having a greater section.

The first process has the defect of not being regulatable. The difficulty will in fact be understood which there is in defining the composition and the physical state of the constituents of a nozzle which should be corroded in a regular way by the metal. Moreover, this process assumes that the temperature of the metal remains constant from one casting to another. When in fact it is otherwise, the nozzle which is more attached by hot metal than by a cold metal enlarges more quickly the hotter the metal, a result which is the converse of that which is required. Now in practice the castings of metal have not all the same temperature, and this process, however simple it may be, must none the less be rejected.

The Batty process above referred to has not these disadvantages; it is rational and adjustable but it necessitates a mechanical device which however simple is still too complicated having regard to the conditions of working in steel works, foundries and other factories where metal is cast.

The present invention remedies these disadvantages and puts at the disposal of the metallurgist simple and efficacious means permitting at will the section of the nozzle to be varied during casting in a regular manner from one casting to another and also permitting to adapt from the beginning of the casting, the section of the nozzle to the temperature of the metal. Thanks to these means it is also possible, in case the casting orifice is obturated, to instantaneously re-establish the casting.

These means consist on the one hand in forming the nozzle of a refractory material possessing a sufficiently high mechanical resistance to be able to resist the forces which a nozzle will normally have to withstand, but nevertheless sufficiently weak so that it is possible to section the nozzle at desired points and on the other hand in imparting to this nozzle a variable section narrowing towards the bottom and a length such that by sectioning or breaking the nozzle and shortening it, increasing flow sections are offered to the metal. By sectioning the nozzle it should be understood as well a sectioning obtained by a cutting action as by a breaking action.

The flow channel of the nozzle is for this purpose formed either of a succession of cylindrical or substantially cylindrical parts whose sections are smaller and smaller as they approach the outlet, or a frustoconical or substantially conical channel narrowing towards the outlet of the nozzle.

Zones of lower resistance are if desired created by notches or circular grooves so as to facilitate the sectioning of the nozzle at determined points.

To utilize the nozzle according to the invention it is sectioned at the desired point to obtain the pouring orifice of desired dimensions, for example by employing a cutting member at that level of the nozzle which comprises the flow section which it is desired to obtain.

The process and the apparatus are as seen very simple; no mechanical device is necessary. In practice within the limit of dimensions of the nozzle the flow section may be regulated as desired. The shortening may take place in one or several stages according as to whether one has use of one or more than two sections. One may thus compensate readily and regularly the variations of temperature and pressure which are exhibited during the same cast, this being done by shortening the nozzle by the quantity which corresponds to the new section necessary at the considered moment. The variations of temperature of the metal from one cast to another can also be compensated in use for such castings made under variable initial conditions of temperature, identical nozzles which have been previously cut at different lengths corresponding each to the said temperature. By means of such a nozzle it is also possible to reestablish the outflow of the metal when the casting orifice becomes obturated and if the limit of the possibility of again sectioning the nozzle has not yet been reached.

In any case, the operation of modification of sections takes place in a few seconds.

The invention is illustrated in the accompanying drawing, in which Figures 1-4 are in their left halves diametrical sections and in their right halves outside elevations of four different forms of nozzle; Figure 5 shows on a smaller scale a pair of shears for sectioning the nozzle.

In the form of construction of Figure 1, the nozzle comprises in the ordinary way a head 1 extended by a limb 2 but instead of this limb being short as is ordinarily the case it is extended to 3 and its interior channel 4 diminishes in section from above to below. By sectioning the limb of the nozzle for example along the planes A—B, B—B, the minimum section offered to the passage of the metal is varied by creating besides the initial section s_1 larger sections such as s_2, s_3 .

20 In Figure 2 is shown a similar nozzle but which comprises grooves 5, 6, 7 facilitating sectioning corresponding with predetermined pouring sections s_2, s_3, s_4 .

25 In the embodiment of Figure 3, the limb 2 of the nozzle is represented shorter than in Figures 1 and 2. The channel 4 of section s_2 comprises a narrowed portion 8 of section s_1 . Above this section s_1 the limb 2 of the nozzle is notched by a circular groove 9. By cutting off the nozzle at 30 the height of this groove the flow section passes from s_1 to s_2 .

35 In Figure 4 which corresponds to a nozzle of the same kind as that of Figure 3, the limb 2 of the nozzle is more elongated and there are two 35 constrictions 10 and 11 in the flow channel and two grooves 12 and 13. The casting being commenced with the section s_1 , the nozzle is afterwards cut during the casting, at 12 to obtain the section s_2 and then at 13 to obtain the section s_3 .

40 Instead of grooves one may provide notches for starting breaking such as those shown at a and b of Figure 1. Wherever the word "groove" is used in the present specification and in the appended claim a "notch" is meant as well.

45 To produce sectioning there will be used for example a pair of shears such as that shown in Figure 5, comprising two handle members 14 and 15, pivoted at 16 and two blades 17 and 18 with which the limb of the nozzle will be cut at 50 the desired level.

50 In the case of a nozzle of the type of Figure 3, one may simply break the lower part of the limb by a blow with an iron bar, given below the groove 9.

55 With the object of avoiding any disturbance in

pouring as a consequence of an accidental crack- 5 ing produced in the body of the nozzle, the rings, such as 19, which bound the grooves, may ad- vantageously be provided with a collar.

As material for the formation of the nozzle 10 there may be utilised in particular that called "graphite" in commerce and which is formed of a mixture of carbon and clay.

15 In the appended claim when reference is made to a channel, successive sections of which in- 10 crease from the outlet to the inlet, it should be understood that such an expression designates not only sections successively and regularly in- 15 creasing so as to confer to the channel a frusto conical or substantially frusto-conical shape, but also sections increasing in the shape of successive cylindrical or substantially cylindrical portions, 20 as hereabove described in relation with Figures 1 to 4.

25 It should be also understood that when refer- 20 ence is made to a nozzle having a section of less resistance, that such an expression designates a nozzle provided with one section of less resistance or with a plurality of such sections. In partic- 25 ular, in the case of a nozzle in which the channel is formed of successive cylindrical portions of in- 30 creasing transverse areas from the outlet to the inlet, the said piece may have a plurality of such cylindrical sections. It should also be understood that the said section of less resistance may be 30 constituted by any suitable means and in partic- 35 ular by means of an outer groove.

It should be lastly understood that when ref- 35 erence is made to shortening a channel during the casting of the metal, that this operation can 35 be made once, or if necessary, several times dur- 40 ing the one and the same casting.

What I claim is:

40 A nozzle for casting molten metal from a re- 40 ceptacle, comprising a single unitary refractory structure including a head adapted to fit within the receptacle and an extension extending a con- 45 siderable distance below the receptacle, said ex- 45 tension provided with a longitudinal flow channel successive cross sections of which increase from 50 the outlet to the inlet thereof, said extension having a weakening groove or notch at at least 50 one point of its length corresponding to an in- 55 creased channel cross section as compared with the channel cross section at its outlet, whereby 55 the extension may be readily broken at said 55 weakening groove or notch to provide an in- 60 creased flow of molten metal.
